TELECOMMUNICATION SWITCHING
SYSTEM

Gerald Deakin, New York, N. Y., assignor to International Standard Electric Corporation, New York, N. Y., a corporation of Delaware

Application August 28, 1943, Serial No. 500,411

22 Claims. (Cl. 179—18)

1

This invention relates to new and useful improvements in telecommunication switching systems and more particularly to selector control circuits for such systems.

The object of the invention is accurately and rapidly to control a switch in the performance of a selective operation, e. g. the seizure of a line.

My co-pending application, Serial No. 484,184, filed April 23, 1943, now Patent No. 2,380,950, dated Aug. 7, 1945, and the co-pending application of Henry F. Herbig, Serial No. 485,827, filed May 6, 1943, now Patent No. 2,354,682, dated Aug. 1, 1944, disclose telephone systems in which a gas valve in a register controller fires when a selector switch tests a free line. A relay will then operate to remove ground from certain relays in the register and from a relay and a clutch magnet in the selector. Thus the selector is stopped and upon the de-energization of the selector relay a busy-ing potential is placed on the test terminals through which the trunk or lines are accessible. From the moment the idle line is encountered until it is made busy, a period of 4,000-8,000 microseconds elapses. Short as this delay is, it will sometimes happen that a gas valve controlling a second selector will fire during this period and cause the seizure of the same line by two selectors.

Further to guarantee against double connections, it has been the practice to make the test twice. Such double test may be made, for instance, by two electromagnetic test relays, first over one brush and then over a second brush of the selector. However, the twin test relays are always tested for a fixed condition. While the arrangement is effective against double connections, it does not afford protection against over-steps which may result in wrong or double connections.

According to the present invention, means are provided materially to reduce the period between the above-mentioned testing and energizing conditions of a relay. In the exemplification of the invention hereinafter disclosed this delay is reduced to 200-100 microseconds. In a time so short the possibility of double testing is, for all practical purposes, eliminated.

I accomplish this by using electronic means such as a gas valve or other electronic switch for testing the line. In accordance with the present embodiment of the invention, the gas valve first tests twice, preferably first over one and then over a second brush of the selector switch.

A trunk may become free just as the selector test brush is about to leave the test terminal

2

and the selector may overstep to a busy terminal while there is still time to fire the gas valve. To guard against this, according to another feature of the present invention, the second test is always made for the same potentials as the first test so as to prevent seizure of the selected terminals and stop the progress of the connection if the second test does not find the same condition as the first test. Should the selector over-step to a free trunk to which the same potential is applied as to the previous trunk, then that trunk will be seized and the connection will proceed in the usual way. Should, however, the overstep be to a free trunk having a different potential, or to a busy trunk or to the space between two terminals, then establishment of the connection will be discontinued.

The invention will now be explained with the aid of the drawing which diagrammatically illustrates as much of an automatic telephone system register and a selector controlled thereby as is necessary for an understanding of the invention.

It is assumed that a calling line has been connected to a second selector and that the register has been set by the calling subscriber to control the numerical operation of the second selector.

As described in my co-pending application, a register switch ED of which only one terminal bank is shown advances from position 1 to position 2 when dialing commences and in so doing will cause a relay RSR in the register to operate. This will connect ground at the armature of relay GVR over the back contact of this relay and the right-hand armature and front contact of RSR to the *a* wire connected over the first group selector to the *A* talking brush of the second group selector. Relay AR in the second selector is connected with this wire over the normally closed contact ONC1. The relay becomes energized and locks up over its left-hand front contact and armature 3, and connects clutch magnet P of the selector over its armature 4 and front contact in parallel with its own locking circuit.

Over its armature 1 and back contact the relay AR disconnects the *b* wire from the normal test potential —N which may be connected to it over an off-normal contact ONC4 and the armature 1 and front contact of relay BR. The *b* wire will now be connected over the armature 1 and front contact of AR, and armature 2 and front contact of relay BR to the test brush T of the selector. The relay BR was energized and locked up immediately upon the seizure of the second group selector by the first group selector over a circuit

including the armature 4 and front contact of the BR relay associated with the first selector (which is like the second selector) resistance 1R2 in the second selector, the c wire and ONC2.

At this stage, a slow releasing relay RSR2 in the register which was energized by RSR connects the b wire to the cathode of a triode V1 and the grid of a triode V2. This slight delay is introduced to prevent a premature and false second test to the test potential —N which would occur if relay AR in the selector failed to break the back contact of armature 1 before RSR2 in the register 2 made its front contact.

Assuming that the calling subscriber has set the register switch brush RB to a terminal to which —N potential is connected, when owing to the energizing of the clutch magnet P the selector brush T is moved into engagement with a free terminal having the same potential, the gas valve GV will be fired and will cause the operation of relay GVR. This is so because when the same potentials are applied to the electrodes of the two triodes, the potential applied over resistances R3 and R5 from the high tension battery to control electrode CE2 will be such as to bring about the firing of the gas valve, provided that normal test potential is applied to the other control electrode CE1. The operating circuit of GVR may be traced from a source of potential —N in the third group selector (identical with the first and second selectors), a resistance 1RT, the ONC4 contact of the third group selector, the armature 1 and back contact of the BR relay of this selector, terminal and test brush T of the second selector, front contact and armature 2 of BR, front contact and armature 1 of AR, the b wire, armature and front contact RSR2, the control electrode CE1 and main gap electrode MG of gas valve GV, winding of GVR, the back contact and armature of a relay GSR to high tension battery. The instant GV fires, the potential applied to the T brush and, therefore, to the multiple test terminals with which it is in engagement, is changed on account of the connection of this high tension battery over the ionized path in gas valve GV. The normal test potentials are of the order of —2 volts to —26 volts. When the above traced test circuit is closed, these negative potentials are increased to 50–75 volts depending on the value of resistance 1RT. This change of potential makes the selected trunk instantly busy and guards it against seizure by another selector since no other gas valve could fire when such potential is applied to its control electrode CE1. It will be seen, therefore, that GV acts as an electronic switch instantaneously to busy the line seized by the selector.

GVR removes ground from the a wire and de-energizes RSR, AR and the clutch magnet P. AR opens its locking circuit, disconnects the b wire from the T brush. This wire is now connected only to the B brush. However, before the T brush is disconnected from the b wire, it is connected over the armature 2 and front contact of relay BR, armature 2 and back contact of relay AR to the t wire and therethrough to a ground at the first group selector. Thus the busy guard on the T terminal is not broken during the transfer.

The de-energization of P will stop the second group selector, whereupon brushes A, B and C make contact with their respective terminals. The b wire of the selected third selector is now connected through to the register. The off-normal contacts ONC1, 2 and 4 open when the

selector leaves its normal position and before it tests the first terminal. ONC3 closes when the other off-normal contacts open.

In the register, GVR will cause the energization of GSR which opens the high tension battery connection long enough to de-ionize gas valve GV and to release GVR. This relay will open the circuit of GSR, but before the latter opens its front contact it will cause the energization of a slow releasing relay GRR by ground applied over the back contact of GVR. GRR locks up over the front contact of RSR2 which did not have time to de-energize during the brief operation of RSR.

When GSR again makes its back contact, the trunk selected by the second selector is tested for a second time, this time for potential —N over the B brush of the second selector and the b wire. This potential is now applied to the B terminal over armature 1 and front contact of the third selector BR relay. Normally, the potential found by the B brush is the same as the potential found by the T brush. Thus GV will fire for the second time and cause the operation of GVR which in this case will advance the out control switch EO of the register over a front contact of GRR. The relay GSR will again be energized and cause the de-ionization of GV and the register circuit will be advanced to control the performance of the next selection.

Should two second group selectors test simultaneously during the short interval of 100 microseconds, then the two associated registers will operate simultaneously and the two selectors will stop on the multiple terminals of the same third selector. However, it is highly improbable that the time constants of the relays of both selectors and registers will be identical. One will busy the B terminal before it is tested by the other. The gas valve GV employed in the last-mentioned connection will, therefore, not fire and when the associated relay RSR2 releases, a circuit will be closed from ground over the back contact of RSR2, the front contact of GRR to a relay DAR. As described in my co-pending application, this causes the release of the register and of the partially established connection and the application of a busy tone to the calling line.

If, for any reason, the second selector oversteps and comes to rest with its brushes between two terminals, then no potential will be found by the B brush and when the second test is made, the connection will be released as just described.

Should the selector overstep and come to rest on a free trunk of the same numerical group, then the same potential —N will be found on the terminal by brush B. The third selector will be seized and the connection will proceed in the normal way.

Should the selector overstep and come to rest with its brushes on the free trunk of a different numerical group, then the potential encountered by the B brush will be different from —N and GV will not fire. The connection will, therefore, be released as previously described.

If the selector oversteps and stops with its brushes on a busy connection, then the potential applied to the b wire will be the same as of the talking circuit at that point. If the talking circuit is open, then the potential will be —48 volts. If it is closed through a low resistance line and a sub-station set of 50 ohms, then the potential will be —26 volts. This potential is not used for trunk selection and thus the second selector will release without disturbing the busy connection.

tion and the busy condition of each set of terminals, first over the brush cooperating with said one and then over said another terminal, and electromagnetic means in each selector for controlling the seizure of a terminal set by the selector and controlled by the testing means only if the same potentials are successively applied over both terminals.

12. In an automatic telephone exchange system, a plurality of lines, means including a group of selector switches for establishing a talking connection between a calling and a called line, a register controlled in accordance with the designation of the called line for controlling a selector to establish the connection, each of said selectors having a bank of multiple terminals and a set of brushes cooperating therewith, sources of different potentials indicating the busy or idle condition of the terminals, testing means associated with the register for testing the condition of each set of terminals, means for connecting said testing means twice in succession with the brushes of the selector under control, and electromagnetic means in each selector controlled by the testing means to seize a set of terminals only if the same potentials are successively applied over the brushes to the testing means.

13. In an automatic telephone exchange system, a plurality of lines, means including a group of selector switches for establishing a talking connection between a calling and a called line, a register controlled in accordance with the designation of the called line for controlling a selector to establish the connection, each of said selectors having a bank of multiple terminals and a set of talking and test brushes cooperating therewith, sources of different potentials indicating the positions of the terminals in the banks, contacts for connecting said potentials normally with a test terminal and when the set of terminals is seized with a terminal cooperating with a talking brush, testing means associated with the register for testing the location and the busy condition of each set of terminals, first over the test brush and then over a talking brush of the selector taken into use, and electromagnetic means in each selector controlled by the testing means to seize a set of terminals only if the same potentials are successively applied over both terminals.

14. In an automatic telephone exchange system, a plurality of lines, means including groups of selector switches for establishing a talking connection between a calling and a called line, a register controlled in accordance with the designation of the called line for successively controlling a selector in each group to establish the connection, each of said selectors having a bank of multiple terminals and a set of talking and test brushes cooperating therewith, sources of different D. C. potentials indicating the positions of the terminals in the banks, contacts in each selector for connecting said potentials normally with a test terminal and when seized with a talking terminal in the preceding multiple bank over which the selector may be seized, testing means associated with the register for testing the location and the busy condition of each set of terminals, first over the test brush and then over a talking brush of the selector taken into use, and electromagnetic means in each selector controlled by testing means to control the seizure of a set of terminals only if the same potentials are successively applied thereto.

15. In combination, a selector having a bank of terminal sets and a set of cooperating brushes, a

magnet for controlling the seizure by the brushes of a set of terminals, sources of different potentials, connections for applying different potentials to the terminals of a set, a variably operable register for controlling the selector magnet and arranged to select a potential designating the location of a desired terminal, a multi-electrode discharge device, connections from the electrodes of said device to the register and to the selector

- 5 10 15 20 25 30 35 40 45 50 55 60 65 70 75
- brushes, means for closing twice in succession the connection between the device and the selector brushes, a circuit for said magnet controlled by said discharge device depending on the relationship of the potentials applied to the connections and means for seizing a set of terminals only if the same potentials are applied over the selector brushes to the device during its first and second connection therewith.

16. In combination, a selector having a bank of terminal sets and a set of cooperating brushes, a magnet for controlling the setting of the brushes on a set of terminals, sources of different potentials, connections for applying different potentials to the terminals cooperating with two brushes, said potentials designating the positions of said terminals in the bank and the busy and idle condition thereof, a variably operable register for controlling the selector magnet and arranged to select a potential designating the location of a desired terminal, a multi-electrode discharge device, connections from the electrodes of said device to the register and to said one of the brushes, a contact in the selector for extending the connection from the discharge device to another brush and a circuit for said magnet controlled by said discharge device depending on the relationship of the potentials applied to the connections.

17. In combination, a selector having a bank of terminal sets and a set of cooperating brushes, a magnet in the selector for controlling the seizing by the brushes of a set of terminals, sources of different D. C. potentials, connections for applying different potentials to the terminals, said potentials designating the positions of said terminals in the bank and the busy and idle condition thereof, a variably operable register for controlling the selector magnet, said register including a variably operable switching device arranged to select a potential designating the location of a desired terminal set, said register also including a gas valve, having control and main gap electrodes, and a multi-electrode discharge device, connections from the electrodes of said device to the register switch and to one of the brushes, contacts in the selector for twice completing the connection from the discharge device to the brushes, a connection from a control electrode of the gas valve to the last-mentioned connection, said discharge device and gas valve being so adjusted that the latter strikes only when the potentials applied to both connections of the discharge device bear a predetermined relationship to one another and the same potential is applied to the control electrode of the gas valve during both operations of the selector contacts and a circuit for said magnet controlled by said gas valve.

18. In combination, a selector having a bank of terminal sets and a set of cooperating brushes, a magnet in the selector for controlling the setting of the brushes on a set of terminals, sources of different D. C. potentials, connections for applying different potentials to the terminals cooperating with two brushes, said potentials des-

While in the register circuit I have illustrated only one gas valve, a second valve may be used in parallel therewith as disclosed in my said co-pending application. In this case, however, one of the control electrodes of the second gas valve should be connected to the conductor leading to the right-hand front contact of RSR2 instead of to ground as shown in my said co-pending application.

What is claimed is:

1. In combination, a switch having a first and a plurality of second sets of cooperating contacts, a source of potentials, means for applying a potential to a contact in each second set, testing means responsive to the potential so applied, a circuit for connecting the testing means to one contact of the first set and therethrough to the contact of the second set cooperating therewith and electronic means for instantaneously altering the potential applied to the contact of said second set to prevent the seizure thereof.

2. In combination, a register, a selector controlled thereby and having a bank of multiple terminals and a set of brushes cooperating therewith, a source of potentials, means for applying a potential to said terminals to indicate the condition thereof, electronic testing means responsive to a predetermined potential connected to said brushes and therethrough to the terminals engaged thereby, and a circuit closed simultaneously with the functioning of the testing means for altering the potential existing on the connected terminals to prevent their seizure.

3. In combination, a register, a selector controlled thereby and having a bank of multiple terminals and a set of brushes cooperating therewith, a source of potentials, contacts for applying a potential to a set of terminals to indicate the condition thereof, a gas valve responsive to said potentials, a circuit for connecting the valve to said brushes and therethrough to the set of terminals engaged thereby, a circuit for said gas valve to ionize it only when a predetermined potential exists on the set of terminals with which it is connected, and a source of potential connected over the gas valve to the terminals engaged by the brushes for altering the potential existing on the terminals upon the ionization of the gas valve.

4. In combination, a register, a selector controlled thereby and having a bank of multiple terminals and a set of brushes cooperating therewith, a source of potentials, contacts for applying potential to a set of terminals to indicate the condition thereof, an electronic switch responsive to said potentials, a circuit for connecting the electronic switch to said brushes and therethrough to the set of terminals engaged thereby, said switch being adjusted to operate only when a predetermined potential exists on the terminals with which it is connected, and a circuit for altering the potential existing on a terminal controlled by said electronic switch.

5. In a telecommunication switching system, a selector switch having a test brush and a plurality of multiple test terminals, a source of potentials, means for applying predetermined potential to said test terminals to indicate the condition thereof, a magnet for controlling the movement of said test brush over said test terminals, a relay for controlling the operation of said magnet to arrest said brush when it engages a terminal on which a predetermined potential exists, and an electronic switch controlling said

relay and altering the potential existing on the test terminal to prevent its seizure.

6. In a telecommunication switching system, a group of selector switches, each having a test brush and a plurality of multiple test terminals, a source of potentials, means for applying predetermined potentials to said test terminals, depending on the idle or busy condition thereof, a magnet for controlling the movement of said test brush over said test terminals, means for controlling the operation of said magnet to arrest said brush when it engages an idle test terminal, and an electronic switch for applying a different predetermined busy potential to said test brush when its arrest is initiated by the actuation of said last-mentioned means.

7. In combination, a first switch, a second switch controlled thereby, having two sets of contacts, and means for causing the contacts to co-operate, for performing a predetermined switching operation, a source of potentials arranged to be connected to one set of contacts, testing means responsive to said potentials, means for connecting the testing means twice in succession to the second set of contacts, and means controlled by the testing means for allowing said contacts to perform said switching operation only if the potentials which are successively applied bear a predetermined relationship to one another.

8. In combination, a register, a selector controlled thereby and having a bank of multiple terminals and a set of brushes cooperating therewith, a source of potentials arranged to be connected to said terminals, an electronic switch responsive to said potentials, means for connecting the electronic switch twice in succession to said brushes, and means controlled by the electronic switch for seizing a set of terminals only if the potentials successively applied thereon to bear a predetermined relationship to one another.

9. In combination, a register, a selector controlled thereby and having a bank of multiple terminals and a set of brushes cooperating therewith, a source of potentials arranged to be connected to said terminals, a gas valve responsive to said potentials, means for operatively connecting the valve twice in succession to said brushes, and means controlled by the valve for seizing a set of terminals only if the same potentials are successively applied thereto.

10. In combination, a selector, a register for controlling the selector, said selector having a bank of multiple terminals and a set of brushes cooperating therewith, sources of potentials indicating the busy and idle condition of the terminals, contacts for connecting said potentials normally with one and when seized with another terminal in a set, testing means associated with the register for testing the condition of each set of terminals, first over the brush cooperating with said one and then over said another terminal, and means in said selector controlled by the testing means to seize a set of terminals only if the same potentials are successively applied over both terminals.

11. In combination, a group of selectors, a register for controlling a selector, said selector having a bank of multiple terminal sets and a set of brushes cooperating therewith, sources of different potentials indicating the positions of the terminals in the banks, contacts for connecting said potentials normally with one and when seized with another terminal in a set, testing means associated with the register for testing the loca-

ignating the positions of said terminals in the bank and the busy and idle condition thereof, a variably operable register for controlling the selector magnet, said register including a variably operable switching device arranged to select a potential designating the location of a desired terminal, said register also including a gas valve, having control and main gap electrodes, and a multi-electrode discharge device, connections from the electrodes of said device to the register switch and to one of the two brushes, a contact in the selector for extending the connection from the discharge device to the other of the two brushes, a connection from a control electrode of the gas valve to the last-mentioned connection, said discharge device and gas valve being so adjusted that the latter strikes only when the potentials applied to both connections of the discharge device bear a predetermined relationship to one another and an idle potential is applied to the control electrode of the gas valve, and a circuit for said magnet controlled by said gas valve.

19. In a telephone exchange system, a plurality of lines, means including a selector switch for establishing a talking connection between a calling and a called line, said selector switch having a bank of terminal sets and a set of cooperating brushes, including a first and a second talking brush and a test brush, a magnet in the selector for controlling the seizure by the brushes of a set of terminals, sources of different D. C. potentials, connections for applying different potentials to the terminals cooperating with the test brush and one of the talking brushes, said potentials designating the positions of said terminals in the bank and the busy and idle condition thereof, a register variably operable in accordance with the designation of the called line for controlling the selector magnet, said register including a variably operable switching device arranged to select a potential designating the location of a desired terminal, said register also including a gas valve, having control and main gap electrodes, and a multi-electrode discharge device, connections from the electrodes of said device to the register switch and to said one of the talking brushes of the selector switch, a relay in the selector for extending the connection from the discharge device to the test brush, a connection from a control electrode of the gas valve to the last-mentioned connection, said discharge device and gas valve being so adjusted that the latter strikes only when the same potentials are applied to both connections of the discharge device and an idle potential is applied to the control electrode of the gas valve, and a circuit for said magnet controlled by said gas valve.

20. In a telephone exchange system, a plurality of lines, means including one of a group of selector switches for establishing a talking connection between a calling and a called line, each of said selector switches having a multiplied bank of terminal sets and a set of cooperating brushes, including a first and second talking brush and a test brush, a magnet in each selector for controlling the seizure by the brushes of a set of terminals, sources of different D. C. potentials, connections for applying different potentials to the terminals cooperating with the test brush and one of the talking brushes, said potentials designating the positions of said terminals in the bank, a register variably operable in accordance with the designation of the called line for controlling the magnet of the selector taken into use, said register including a variably operable switch-

ing device arranged to select a potential designating the location of a desired terminal, said register also including a gas valve, having two control and main gap electrodes, and two triodes, a first connection from the grid of the first and the cathode of the second triode to the register switch, a second connection from the cathode of the first and the grid of the second triode to said one of the talking brushes of the selector in use, a relay in said selector for extending the second connection to the test brush, a connection from a control electrode of the gas valve to the second connection, a connection from the second control electrode of the gas valve to the anodes of the two triodes, said discharge device and gas valve being so adjusted that the latter strikes only when the same potentials are applied to the first and second connections of the triodes and the brushes of only one selector engage a set of terminals, and a circuit for said magnet controlled by said gas valve.

21. In a telephone system, a plurality of lines, means including one of a group of selectors for interconnecting calling and called lines, each of said selectors having a multiplied bank of terminal sets and a set of brushes cooperating therewith, including a first and a second talking conductor brush and a test brush, a magnet and a relay for each selector for controlling the seizure by the brushes of a set of terminals, conductors leading to said brushes, means including a variably operable register for controlling the setting of the selector brushes of the selector taken into use, sources of different D. C. potentials are applied to the terminals cooperating with the second talking and test brushes to designate their location and their idle and busy condition, said register comprising a switch having a row of terminals and a brush cooperating therewith, connections for applying to the terminals of the register switch potentials corresponding to those designating locations of selector terminals, a high tension source, two triodes, a gas valve and relays in said register, a connection from the high tension source to the anodes of the triodes and a control electrode of the gas valve, an energizing circuit closed by the register relays for the relay and the magnet of the selector taken into use over the conductor leading to the first talking brush, a connection to a source of potential extending over a back contact of the selector relay and the conductor leading to the second talking brush, a connection extending from the test brush over a back contact of the selector relay to ground and over a front contact of the selector relay to ground and over a front contact of the selector relay to the conductor leading to the second talking brush, a connection from the grid of the first and the cathode of the second triode to the brush of the register switch, a connection from the grid of the second and the cathode of the first triode to the conductor leading to the second talking brush, a second control electrode for the gas valve connected with the conductor leading to the second talking brush, and a main gap electrode for the gas valve connected with one end of the winding of one of the register relays controlling the selector relay circuits, the other end of which is connected with the high tension source, said triodes and gas valve being so adjusted that the latter strikes and operates said one register relay when equal potentials are applied to the grid and cathode connections of the triodes and the brushes of only one selector are connected with the selected set of terminals.

11

22. In a telephone system, a plurality of lines, means including one of a group of selectors for establishing a talking connection between a calling and a called line, each of said selectors having a multiplied bank of terminal sets and a set of brushes cooperating therewith, including a first and a second talking conductor brush and a test brush, a magnet and two relays in each selector for controlling the movement of the brushes over and the seizure by them of a set of terminals, conductors leading to said brushes, means including a variably operable register for controlling the setting of the brushes of a selector taken into use, sources of different D. C. potentials, means including said relays to apply said potentials normally to the terminals cooperating with the test brush and when the selector is taken into use to the terminal cooperating with the second talking brushes, said potentials designating the location and the idle and busy condition of the sets of terminals, said register comprising a switch having a row of terminals and a brush cooperating therewith, connections for applying to the terminals of the register switch potentials corresponding to those designating locations of selector terminals, a first, a second, a third, a fourth and a fifth relay in the register, the second and third relays being slow to release, a high tension source in said register, two triodes and a gas valve in said register, said gas valve having two control electrodes and a main gap electrode, a connection from the high tension source over a back contact of the fourth relay to the anodes of the triodes and a control electrode of the gas valve, a circuit for operating the first relay upon the adjustment of the register to control a selector, said circuit including back contacts of the third and fifth relays, an energizing circuit closed by the first relay for said relay and the magnet of the selector taken into use and including a back contact of the fifth and a front contact of the first relay and the conductor leading to the first talking brush of said selector, a connection to a source of potential extending over a back contact of one and the front contact of the other selector relay and the conductor leading to the second talking brush, a connection extending from the test brush over a back contact of

12

tact of said selector relay and a front contact of the other selector relay to ground and over front contacts of said selector relays to the conductor leading to the second talking brush, a connection from the grid of the first and the cathode of the second triode to the brush of the register switch, a connection from the grid of the second and the cathode of the first triode over a front contact of the second relay to the conductor leading to the second talking brush of the selector taken into use, a connection from the second control electrode to the conductor leading to the second talking brush of said selector, a connection from the main gap electrode to one end of the winding of the fifth relay, the other end of which is connected with the high tension source over a back contact of the fourth relay, said triodes and gas valve being so adjusted that the latter strikes and operates the fifth relay when equal potentials are applied to the grid and cathode connections of the triodes and the brushes of only one selector are connected with a set of terminals, an energizing circuit for the fourth relay closed over a front contact of the fifth relay, an energizing circuit for the third relay controlled over a front contact of the fourth and back contact of the fifth relay, and a locking circuit of the third relay controlled over the front contact of the second relay.
